UNITED STATES PATENT OFFICE.

JOHN F. O'CONNOR, OF CHICAGO, ILLINOIS, ASSIGNEE, BY MESNE ASSIGNMENTS, TO
W. H. MINER, INC., A CORPORATION OF DELAWARE.

SIDE BEARING.

Application filed July 9, 1923. Serial No. 650,208.

This invention relates to improvements in side bearings.

An object of the invention is to provide a side bearing especially adapted for railway cars wherein the anti-friction element is automatically self-centered under the influence of gravity when relieved of load and without the interposition of any means likely to get out of order—such as springs.

10 More specifically, the object of my invention is to provide an anti-friction bearing adapted for attachment to body bolsters of cars and wherein are employed an anti-friction roller and cradles for supporting the 15 roller so arranged that, when the parts have been moved to either side of central normal position, the center of gravity of the cradles and of the roller will be at such points as to automatically influence the return of the supporting cradles with the roller carried thereby to central position.

In the drawing forming a part of this specification, Figure 1 is a vertical sectional view taken through the ends of the body and 20 truck bolsters of a car showing my improvements in connection therewith. In this Figure the dotted lines indicate the extreme position assumed by the parts when moved toward the right, as viewed in Figure 1. 25 Figure 2 is a bottom plan view of the construction illustrated in Figure 1. And Figure 3 is a vertical sectional view corresponding substantially to the section line 3—3 of Figure 1.

30 In said drawings, 10 denotes the upper portion of a truck bolster and 11 the under side of an opposed body bolster. In the drawing, the improved side bearing is shown attached to the body bolster 11, said improved bearing comprising, broadly, a retainer or housing casting A; an anti-friction element proper B; and a pair of supporting cradles C—C.

The housing or retaining member A is 35 preferably in the form of a hollow box-like casting having an upper flat wall 12, depending vertical side walls 13—13 and curved end walls 14—14, the housing being open at the bottom, as clearly shown in Figures 2 and 3. The housing A is provided with suitable lugs 15—15 by which the housing is 40 secured to the body bolster as by the rivets 16. Preferably, a hardened wear plate 17 is employed on the inner side of the housing 45 A to form the upper bearing surface proper,

said plate 17 being inserted through suitable openings 18—18 in the ends of the housing and held in position by rivets 19, the upper ends of said rivets being countersunk flush with the upper surface of the housing casting A. 60

The side walls 13, at the bottom edges thereof, are provided with in-turned horizontally disposed flanges 20—20, the latter having arched or convexed upper bearing surfaces 21 for about two-thirds of the width of the flanges and series of teeth 22—22 for the remaining approximately one-third width of the flanges, the teeth being disposed nearest the anti-friction element B. 65

The anti-friction element B, as shown, is preferably in the form of a true cylinder and has a central aperture to accommodate the pin 23, the ends of which are extended beyond the roller and supported in the cradles C, as shown in Figure 3. The side walls 13 are suitably apertured, as indicated at 24, to permit the insertion of the pin 23 when the parts are elevated and before the wear plate 17 is in position. 70

The two cradles C are of like construction and each is of elliptic form with an upper convex surface 25 and a lower convex bearing surface 26. The bearing surfaces 26 of the cradles roll upon the opposed oppositely convexed bearing surfaces 21 of the housing A. Also, on the lower face each cradle C is provided with an arcuate series of teeth 27 which co-operate with the correspondingly adjacent series of teeth 22 on the housing A. As will be apparent from an inspection of Figure 1, it will be noted that the pin 23 is accommodated in openings in the cradle C which are disposed slightly above the geometrical center of the cradles. 85

When the side bearing is brought into action, the anti-friction element B will first be slightly raised until it is in engagement with the upper bearing surface provided by the plate 17 and the bearing surface on the truck bolster 10. As relative radial movement between the two bolsters takes place, the anti-friction element B will be rolled to one side—as, for instance, to the right-hand side, as shown in Figure 1—during which time it has a true rolling action on both upper and lower bearing surfaces. As the roller is thus moved to one side of central position, the cradles C are rocked about their own convex bearing surfaces 100 105 110

and on the convex bearing surfaces of the housing A until the cradles reach a position such as indicated by the dotted line C' in Figure 1. In this position of the parts, it will be noted that the points of support between the cradle C and the supporting surfaces 21 of the housing A are approximately at the place indicated by the reference character 25 in Figure 1. These points of support are obviously to the right of the center or axis of the roller B and to the right of the center of gravity of the cradles C. In this connection, it will be observed that the centers of gravity of the cradles C will be slightly to the left of the axis of the roller B when the parts are in the position shown by the dotted lines in Figure 1, due to the fact that the axis of the roller is above the geometrical center of the cradles, as heretofore described. With this condition, if the load is removed from the anti-friction element, there is an immediate tendency for the cradles to rock back to their central normal position carrying the anti-friction element therewith, all under the influence of gravity, and thereby returning the parts to normal position and in a condition ready to receive the next actuation. During this return action, it is obvious that the co-operating sets of teeth will serve to prevent slippage of the cradles on the supporting flanges and to always maintain the relative relation desired between the cradles and the retaining member.

Although I have herein shown and described what I now consider the preferred

manner of carrying out my invention, the same is merely illustrative and I contemplate all changes and modifications that come within the scope of the claims appended hereto.

I claim:

1. In a side bearing, the combination with a retainer provided with a bearing surface and supporting ways; of a pair of cradles, each cradle having a lower curved bearing surface adapted to roll upon said ways, said cradles being counterbalanced to normally maintain a state of equilibrium centrally with reference to said container; and an anti-friction element balanced about its axis and pivotally supported at a central point on said cradles.

2. In a side bearing, the combination with a housing adapted to be secured to a bolster, said housing having opposed supporting flanges, each having an arched supporting bearing surface; of a pair of cradles, each cradle having a lower curved bearing surface adapted to roll upon the correspondingly arched supporting surface of said flange, said cradle being counterbalanced to normally maintain a state of equilibrium centrally with reference to said bearing; and an anti-friction roller balanced about its axis and pivotally supported on said cradles centrally thereof.

In witness that I claim the foregoing I have hereunto subscribed my name this 6th day of July, 1923.

JOHN F. O'CONNOR.
